UNITED STATES PATENT OFFICE.

ROBERT D. BRUEGGER, OF WILLISTON, NORTH DAKOTA.

DESIGN FOR A SIGN.

• 57,424.

Specification for Design.

Patented Mar. 29, 1921.

Application filed January 17, 1920. Serial No. 352,219. Term of patent 7 years.

To all whom it may concern:

Be it known that I, ROBERT D. BRUEGGER, a citizen of the United States, residing at Williston, in the county of Williams and State of North Dakota, have invented a new, original, and ornamental Design for a Sign, of which the following is a specification, reference being had to the accompanying drawing, forming part thereof.

The figure is a perspective view of a sign, showing my new design.

I claim:

The ornamental design for a sign, as shown.

ROBERT D. BRUEGGER.
